UNITED STATES PATENT OFFICE.

HARVEY N. MALLERY, OF FLINT, MICHIGAN.

HORSESHOE-HAMMER.

SPECIFICATION forming part of Letters Patent No. 224,023, dated February 3, 1880.

Application filed December 18, 1879.

To all whom it may concern:

Be it known that I, HARVEY N. MALLERY, of Flint, in the county of Genesee and State of Michigan, have invented certain new and 5 useful Improvements in Horseshoe-Hammers; and I do hereby declare that the following is a full, clear, and exact description of the invention, which will enable others skilled in the art to which it appertains to make and use 10 the same, reference being had to the accompanying drawings, which form a part of this specification.

Figure 1 is a perspective view, and Fig. 2 is a longitudinal sectional view.

15 Similar letters of reference indicate corresponding parts in both figures.

This invention relates to an improved hammer intended more particularly for the use of blacksmiths in manufacturing horseshoes; and 20 it consists in certain improvements in the construction of said hammer, which will be hereinafter more fully described, and particularly pointed out in the claim.

In the drawings, A represents the handle, 25 and B the head, of the hammer. One face, C, of the latter is of the usual construction—*i. e.*, flat or convex, with a smooth or polished surface. The other face, D, is beveled toward the front, and is either serrated or provided with

transverse corrugations, as represented in the 30 drawings.

With an ordinarily-constructed hammer great or unusual force is required to sharpen the calks upon a horseshoe, which, during this operation, is held upon the side of the anvil, 35 the end of the tongs resting meanwhile upon the breast of one of the operators.

By my improvement the beveled face of the hammer enables the operator to strike a more direct or square blow, while the serrations or 40 corrugations serve, so to speak, to draw the metal out to a sharp edge or point.

Having thus described my invention, I claim and desire to secure by Letters Patent of the 45 United States—

The herein-described improved hammer, provided with a flat face, C, and beveled face D, having transverse corrugations, substantially as and for the purpose herein shown and specified.

50 In testimony that I claim the foregoing as my own I have hereto affixed my signature in presence of two witnesses.

HARVEY N. MALLERY.
